UNITED STATES PATENT OFFICE.

JOHN GABEL, OF CHICAGO, ILLINOIS.

AUTOMATIC TALKING MACHINE.

1,414,564.

Specification of Letters Patent. Patented May 2, 1922.

Application filed March 15, 1917. Serial No. 154,950.

To all whom it may concern:

Be it known that I, JOHN GABEL, a citizen of the United States, and a resident of Chicago, county of Cook and State of Illinois, 5 have invented certain new and useful Improvements in Automatic Talking Machines, of which the following is a specification.

The invention relates to talking or sound reproducing machines and more particularly 10 to machines in which mechanism is provided for automatically changing the records and shifting the sound box or reproducer. The invention seeks to provide improved means for changing the records and shifting the 15 sound box. A further object of the invention is to provide improved means for rotating the turn table or record support and for operating the record and sound box shifter mechanisms.

20 With these and other objects in view, as will presently appear, the invention consists in the features of improvement hereinafter set forth, illustrated in the accompanying drawings and more particularly pointed out 25 in the appended claims.

In the drawings Figure 1 is a front elevation of the improved machine. Fig. 1^a is a detail view of parts shown in Fig. 1. Fig. 2 is a rear elevation. Figs. 3 and 4 are 30 enlarged rear elevations of portions of the mechanism with parts shown in changed positions. Fig. 5 is an enlarged detail view of a portion of the mechanism with parts shown in section on the lines 5—5 of Fig. 6, 35 7 and 8. Fig. 6 is an enlarged end elevation of portions of the mechanism, parts being shown in section on the lines 6—6 of Figs. 1, 5, 7 and 8. Fig. 6^a is a detail view of a portion of Fig. 6 with the parts shown in 40 changed position. Fig. 7 is a plan detail view with parts shown in section on lines 7—7 of Figs 2, 3, 5 and 6. Fig. 8 is a detail plan view of the record and sound box shifter mechanism with parts of the frame shown 45 in section on the line 8—8 of Fig. 1. Figs. 8, 9 and 9^a are detail views of parts shown in Fig. 8. Fig. 10 is an enlarged detail section on lines 10—10 of Figs. 1 and 8. Figs. 10^a and 10^b are detail views of portions shown in 50 Figs. 8 and 10 and illustrating in front elevation and in different positions, the mechanism for lifting the sound box out of en-

gagement with the record at the end of the reproduction of the record, the turn table and record being shown in central section. Fig. 55 10^c is a rear elevation of parts shown in Figs. 10^a and 10^b.

The preferred embodiment of the present invention is similar in construction to those set forth in prior Letters Patent of the 60 United States, issued to me, No. 1,134,603 dated April 6, 1915, and No. 1,182,551 dated May 9, 1916, and in a companion application filed by me in the United States Patent Office January 4, 1916, Serial No. 70,131. 65

The improved machine is mounted upon a frame work and is inclosed in a suitable casing. The casing is not shown but may be similar in construction to that illustrated in the above mentioned prior patents. The 70 frame work shown comprises upper and lower, substantially rectangular, cast metal frames 1 and 2 which are connected at their corners by vertical rods 3 and which are also connected intermediate their ends and at the 75 front and rear of the machine by vertical straps 4. A short cast metal frame 5 is fixed to the central portions of the front and rear straps 4 and supports the turn table and parts of the turn table operating mechanism. 80 The mechanism whereby the changing of the records is effected is, for the most part, mounted upon the heavy lower cast metal frame 1. The entire frame work can be removably mounted within a suitable casing 85 and preferably upon supporting lugs or brackets 6 (see Fig. 1) secured to the end walls of the casing.

The record support or turn table A (see 90 Figs. 5 and 8) is mounted in the upper central portion of the frame work upon the upper end of a short vertical shaft a. The shaft a is journaled immediately below the hub of the turn table in a bracket 7 and its lower conical end is journaled in an upright 95 8 on a bracket 9. The brackets 7 and 9 (see Figs. 5 and 6) are horizontally disposed, are preferably formed of cast metal and are connected together by a series of vertical studs 10. The upper bracket 7, as 100 most clearly shown in Fig. 6, is connected to and carried by the cast metal frame 5. The turn table is driven by a small electric motor B mounted on a bracket 11 that is

secured to and depends from the front right-hand portion of the lower frame 1. Governor controlled friction gearing is interposed between the motor and the turn table 5 to maintain the speed of the latter uniform. In the construction shown, the shaft *a* is provided with a spur gear 12 which meshes with a pinion 13 (see Fig. 6) on the upper end of a short vertical shaft 14 which is 10 journaled in the horizontal brackets 7 and 9. A friction disk 15 on the shaft 14 is provided with a lower horizontal working face which is arranged to engage a friction drive wheel 16 on a short horizontal shaft 15 17. The latter shaft extends longitudinally in the machine frame and is journaled at its ends, as most clearly shown in Fig. 5, upon a pair of upright brackets 18 and 19 which are secured to and rise from the lower 20 horizontal frame 1. The friction disk 15 is provided with a long comparatively heavy hub 15' which is vertically slotted at its upper end (see Fig. 1) to receive a pin 14' extending through the shaft 14. The disk 25 is thus connected to the shaft 14 to rotate it and the turn table through the medium of the gears 12 and 13, but the disk is free to shift vertically to a slight extent on the shaft 14 and is held by gravity into contact 30 with the friction drive wheel 16, which is preferably covered with leather or other suitable friction material. The wheel 16 is mounted upon a short horizontal shaft 17 and the latter is journaled at its ends in 35 brackets 18 and 19 that rise from the lower frame 1.

At one end the shaft 17 is provided with a grooved pulley *b*' which is connected by a belt 20 to a pulley *b* on the shaft of the electric motor B. The bracket 11 is preferably vertically slotted (see Fig. 1) and is adjustably connected to the frame 1 by screw bolts 21 so that the motor and motor shaft can be properly adjusted to place the desired tension on the drive belt 20. The hub of the pulley *b*' is fixed to the shaft 17, but the hub of the friction wheel 16 is slotted to receive a key 22 (see Fig. 7) so that while the friction wheel rotates with the 50 shaft it can shift longitudinally thereon. The position of the friction wheel is determined by a fly-ball governor comprising pairs of arms 23 pivotally connected to one another and to the hubs of the wheels *d*' 55 and 16 and provided with governor balls or weights C. A spring 24 coiled about the shaft 17 between the hubs of the wheels *b*' and 16 tends to move the latter wheel toward the center of the friction disk 15 60 while the pull of the governor balls C on the arms 23 tends to move the wheel away from the center of the friction disk. The latter is thus adjusted during the operation of the machine to compensate for any 65 variations in the speed of the electric motor

and thereby maintain the speed of the turn table uniform.

Preferably also, a governor brake is applied to the turn table. For this purpose the gear 12 meshes with the pinion 25 on the upper end of the short vertical shaft 26 journaled in the brackets 7 and 9. Weighted spring arms D are connected at their lower ends to a collar 27 fixed to the shaft and at their upper ends to a friction disk *d* slidably mounted on the shaft 26. This disk bears upon felt or like pads on the forked inner end of a brake arm or lever *d*'. The latter is pivoted (see Fig. 6) on the frame 5 and an adjusting screw 28 engages its outer end. By adjusting the brake lever *d*' the speed of the turn table may be regulated as desired, but in any given adjustment of the governor D, it cooperates with the drive wheel controlling governor C to maintain the speed of the turn table uniform.

As in the constructions set forth in the prior patents referred to and in the copending application, the disk records are carried in a pair of magazines E and E' arranged on opposite sides of the turn table A and, as in the construction shown in the copending application, one of the magazines E is designed to hold relatively large records *e* and the other magazine E' is arranged to hold relatively small records *e*'. Each magazine comprises a frame having inwardly projecting pairs of fingers 29 upon which the records are supported, the frame being mounted to slide upon a pair of guide rods 30 fixed at their upper and lower ends to the frames 1 and 2 (see Figs. 1, 2 and 8). Anti-friction rollers 31 and 32 at the upper and lower ends of the magazine frames engage the outer and inner sides respectively of the guide rods 30. Cords 33 attached to each magazine extend upwardly and are fixed to grooved pulleys 34 that are journaled in uprights 35 on the ends of the top frame 2. Spiral cams 36 are fixed to or formed in piece with the grooved pulleys 34 and cords 37 fixed to the cams extend downwardly therefrom and are connected to the upper ends of a pair of heavy springs 38. The lower ends of these springs are connected to adjusting screws 39 which extend through the ends of the lower frame 1 and are provided with thumb nuts 40 (see Fig. 1). These springs partially counter-balance the weight of the magazines and records therein and, because of the spiral cams 36, the springs exert a uniform pull upon the magazines in the different adjusted positions thereof.

The magazines are provided at their lower ends with inwardly projecting arms 41 which rest upon the outer ends of a pair of adjusting shift levers *f*. The latter are pivoted at their inner adjacent ends upon a lug 42 on

the frame 1 and are provided, intermediate their ends, with bevelled abutments 43 which rest upon a pair of notched heart-shaped cams F. The latter are mounted upon a pair 5 of horizontal shafts 44 having ratchet wheels 45 thereon engaged by spring-held roller dogs 46, which serve to hold the magazines in adjusted position with one of the records in each magazine opposite the turn table.

10 The outer end of each shifter arm f is guided by a vertically slotted bracket 47 mounted on the frame 1 (see Figs. 1, 2 and 7). A pair of vertically disposed pins 48 and 49 are arranged to engage the central openings in 15 the records in each magazine, the lower pins being fixed to the brackets 47 and the upper pins being removably mounted in parts 50 on the upper frame 2. Set screws 51 removably hold the upper pins in place. The adjacent, 20 pointed ends of each pair of pins are spaced apart so that the record in each magazine in line with the turn table can be shifted in horizontal direction.

A shifting slide or carriage G (see Figs. 2, 6 and 8) reciprocates upon a pair of horizontal track bars 52 which are fixed to the vertical rods 3 and 4 at the front and rear of the frame. Lugs 53 on the carriage overlap the track bars and studs 54 extend beneath the same. The carriage is provided with curved portions or holders g and g', one of which is adapted to engage and nearly surround one of the large records e and the other engage and nearly surround one of 35 the small records e' as most clearly indicated in Fig. 8. The carriage is of such length that one of the holders thereof will engage a record in position on the turn table and the other holder engaging the record in 40 one or the other of the magazines which is in line with the turn table.

The rear central portion of the carriage G is provided with a depending lug 55 (see Figs. 2 and 6) which has a pivotal pin-and-slot connection with the upper end of a shift lever H, the lower end of which is pivotally mounted on a depending lug 56 at the rear central portion of the lower frame 1. A link 57 pivotally connected at its inner end to 50 the arm H is connected at its outer end by a pivot pin 58 to a swinging arm 59. The arm 59 is preferably formed of cast metal and is of considerable width (see Fig. 7) being pivotally mounted at its lower end on 55 a shaft or pivot pin 59' carried by the frame 1. The inner end of the pivot pin 58 engages a longitudinal slot 60 in the outer end of a link 61 and the inner end of the latter is connected to a crank arm h' on a shaft h.

60 The shaft h (see Figs. 5 and 6) is journalled in suitable bearings in the frame 1 and is provided with a gear 62 that meshes with a pinion 63 on a short horizontal counter shaft 64. The latter is journalled in the lug 65 42 and in a lug 65 on the frame 1 and at its

forward end is provided with a gear 66 which meshes with a pinion 67 on the hub of a vertically disposed friction disk 68. The latter is loosely mounted upon a shaft 69 which is fixed to the upper end of the 70 bracket 19 and projects forwardly therefrom. A spring 70 coiled about the outer end of the shaft extends between the hub of the friction disk and an adjusting nut 71, and this spring serves to hold the friction 75 disk 68 into engagement with a friction drive wheel 72 which is fixed to the shaft 17. The shaft h is thus driven from the motor B and countershaft 17 to reciprocate the carriage G and thereby move the records 80 between the magazines and the turn table. The arm h' is also provided on its outer end with a tooth 73 (see Fig. 5) which cooperates with the teeth of the ratchet wheels 45 to rotate the shaft 44 and heart-shaped cams 85 F and thereby raise and lower the magazines step-by-step.

Means is provided for throwing the record shifting mechanism into and out of operation and preferably also, means is provided 90 for arresting the turn table or record support during the operation of the shifter mechanism. For this purpose, a short horizontal shaft 74 (see Figs. 5, 6 and 7) is journalled on the bracket 9 and is provided 95 with arms J and J' which, as the shaft 74 is oscillated, are arranged to alternately engage the friction disks 15 and 68 and shift the same into and out of engagement with the friction drive wheels 16 and 72. Normally, these parts are in the position shown 100 in Figs. 5, 6 and 7 in which a leather or felt pad on the end of the arm J' engages the disk 68 to hold it away from the drive wheel 72 and thus maintain the record shifter 105 mechanism idle. At the end of the reproduction of the record the shaft 74 is shifted, as hereinafter described, to move the arm J' away from the disk 68 and lift the disk 15 by means of the arm J out of engagement 110 with the drive wheel 16. The rotation of the turn table is thus arrested and the spring 70 forces the disk 68 into engagement with the drive wheel 72 to thereby throw the record shifter mechanism into operation. 115 This shifted position of the controlling arms J and J' is shown in Fig. 6a. As herein-after described, the shifter mechanism is maintained in operation until the main operating shaft h has completed a half revolution. The controlling arms J and J' are then returned to normal position to stop the shifter mechanism and throw the turn table 120 into operation to reproduce the record thereon.

As shown in the drawings, the record shifting carriage G is at one side of the machine with one of the small records e' withdrawn from the magazine E' and in position on the turn table with all of the large 125

records *e* in position in the magazine *E*. At each operation of the shifter mechanism, the shaft *h* and crank arm *h'* are rotated through a half revolution to shift the parts 5 61, 59 and 57 and thereby move the shift lever *H* and carriage *G* to the other side of the machine. One of the records *E* is thus moved from the magazine *e*, into playing 10 position on the turn table and, at the same time, the record *e'* on the turn table is moved back into position in the magazine *E'*. At the next operation, the carriage is shifted back in the opposite direction to restore the record *e* to the magazine *E* and move 15 one of the records *e'* from the magazine *E'* onto the turn table.

It will be noted that when the shifter mechanism is at rest, a record is withdrawn from one of the magazines. To permit the 20 vertical shift of the other or full magazine, the shafts 44 extend to the front of the machine and are provided with knobs or the like so that the user can adjust these shafts to thereby raise and lower the magazines and 25 bring the desired record into line with the turn table. Means must be provided for preventing the vertical shift of the magazine from which a record has been withdrawn. For this purpose the cams *F* and ratchet 30 wheels 45 are loose on the shafts 44 and are connected thereto by spring-held clutch members 75 (see Figs. 5 and 7). These clutch members are operatively connected to the outer ends of a pair of levers 76 which 35 are pivoted intermediate their ends upon the frame 1 and the inner ends of which engage with a rib or flange 77 on the rear face of the gear 62. At one point this flange or 40 rib is provided with a notch 78, and, at the ends of the half revolutions of the shaft *h* and gear 62 thereon, one of the levers 76 will enter the notch and engage its clutch to connect the corresponding shaft 44 with the shifter and cam *F* of the full magazine, but 45 the clutch of the other magazine, from which a record has been withdrawn, will be held in disengaged position. The user of the machine may thus shift one or the other of the magazines to select the next record to be 50 played. As already noted, the dog or pawl 73 on the arm *h'* cooperates alternately with the ratchet wheels 45 to rotate the same one step at a time at the successive half revolutions of the shaft *h* so that if no selections 55 are made by the user, the record shifting mechanism will operate automatically to place the records in the machine in succession on the turn table.

The record on the turn table is held in 60 central position thereon by a pointed pin *K* (see Figs. 5 and 8) mounted on the forward end of a horizontal arm *k* and adapted to extend downwardly through the central opening of the record into a socket in the 65 turn table. The arm *k* is fixed at its rear

end to a vertical rod *k'* (see Fig. 2) which reciprocates through upper and lower guide lugs 79 and 80 at the back of the machine. The lower end of the rod *k'* which is preferably provided with a roller, engages a spiral cam 81 on the rear end of a shaft 82. This shaft is journaled in the lug 56 at its rear end and, at its forward end, in a lug 83 (see Fig. 6) both of which lugs depend from the frame 1. The inner end of the shaft 82 is provided with a gear 84 which is half the size of and meshes with the gear 62, so that shaft 82 makes a complete revolution while the shaft *h* is making a half revolution at each operation of the machine. When the record shifter mechanism is started, shaft *h* and cam 81 are rotated in the direction indicated by the arrows in Fig. 2 and the cam quickly lifts rod *k'*, arm *k* and pin *K* to release the record on the turn table. At the end of the shifting movement of the carriage *G*, the cam 81 lowers the rod *k* and brings the pin *K* into engagement with the next record on the turn table. It should be noted that the initial movement 90 of the shaft *h* and arm *h'* at first takes up the lost motion between the link 61 and the arm 59 so that the record centering pin *K* is lifted before the carriage *G* commences its movement. It should also be noted that the arrangement of the arm *h'* and link 61 is such that the shift of the carriage *G* is completed before the arm *H* finishes its half revolution. This continued movement of the link 61 after the throw of the carriage *G* is 100 completed moves the link relatively to the pin 58 so that the carriage can be moved backward to a slight extent, out of contact with the record on the turn table.

To effect this backward movement of the record shifting slide or carriage, the latter is provided at its rear edge, with lugs 85 having upwardly facing V-shaped notches 86 therein (see Figs. 8 and 8^a). The arm *k* which carries the center pin *K* is provided at its rear end with a downwardly projecting pointed or V-shaped cam lug 87 which is arranged to cooperate with the notches 86 of the lugs 85 on the record slide or shifter. At the end of the movement of the carriage or record shifter in one or the other direction, the crank arm *h'* and link 61 move past a straight line position so that the end of the slot 60 in the link moves away from the pin 58. The shift of the carriage is completed before the cam 81 lowers the rod *k'* and arm *k*. When this occurs, the cam lug 87 engages one of the notched lugs 85 on the carriage or slide and moves it backwardly to a slight extent out of engagement with the record on the turn table so that it does not contact therewith during the reproduction of the record. As indicated in Fig. 8 the record engaging portions *g* and *g'* of the record shifter are slightly larger 130

in diameter than the records themselves to permit this operation. The cooperating cam lugs 87 and 85 and the centering pin K serve to respectively hold the record shifter 5 and the record in position and out of contact with each other during the reproduction of the record. As the records pass between the turn table and the magazines, they are upheld by pairs of guide lugs 89 projecting 10 upwardly from the frame 5. The portions of the carriage G which pass over these lugs are cut away as indicated at 90 to clear the same. As the records of either size vary slightly in diameter, the pin K and pins 48 15 and 49 are provided with pointed ends so that they will properly engage the holes in the records and center the same on the turn table and in the magazines, and each magazine frame is provided with two vertical stop 20 springs 91 (see Fig. 8) for determining the position of the records in the magazines.

In moving the records over the turn table, the carriage G contacts with the upper, felt covered surface of the turn table to prevent 25 the thin records from wedging between these parts, and the turn table itself to properly operate the large records e, must be larger than holder g' of the carriage and only slightly smaller in diameter than the 30 large records. For these reasons, when the carriage is at the left-hand side of the machine, with a small record on the turn table, as shown in Fig. 8, means are provided for raising the right-hand end of the carriage 35 slightly and thus move the holder g' out of contact with the turn table, while the small record e' thereon is being reproduced. This means comprises a push rod 92 (see Figs. 5, 7 and 8) which extends through a guide 40 opening 93 in one of the cross bars of the frame 5 (see Fig. 5) and the lower end of which is connected to one arm 94 of a bell crank lever. This bell crank lever is pivotally mounted on the bracket 19 and the 45 other arm 95 is arranged to be engaged by a stud 96 (see Figs. 6 and 7) on the end of the crank arm h'. As already noted, the arm h' has an additional movement after the shift of the carriage G is completed, 50 and when it has moved the carriage to place a small record on the turn table, this additional movement of the arm h' brings it into engagement with the arm 95 of the bell crank lever, lifts the push rod 92 so that 55 its upper end engages the central portion of the carriage, as shown in Figs. 5 and 6, and slightly lifts and maintains the holder g' out of contact with the turn table during the reproduction of the small record 60 thereon. This lift of the right-hand end of the carriage is permitted by providing notches 97 (see Figs. 1, 2 and 3) in the lower edges of the carriage guide rails 52, the notches being located at proper points 65 to receive the studs 54 which project from

the right-hand end of the carriage. As soon as the arm h' moves from the position shown in Fig. 5, the push rod 92 is lowered by gravity out of the path of the movement of the carriage or slide G and it is not 70 raised to lift the right-hand end of the carriage or slide until the latter is again operated by the shifter mechanism to move a small record and the holder g' over the turn table. 75

As in the construction set forth in the prior patent and application referred to, the sound box or reproducer L is mounted upon the forward end of a hollow arm L' which is connected to a suitable amplifying device. 80 An upturned elbow at the rear end of the arm is provided on its under side with a lug 98 (see Figs. 3 and 10) having an opening 99 therein through which extends a guide rod 100. The horizontal guide rod 100 is removably fixed to a pair of lugs on the upper portion of a cast metal frame 101 which is secured to the upper rear portion of the machine frame. A vertical pivot screw 102 depending from the lug 98 connects the rear 90 end of the sound box arm L' to a yoke 103 having upturned ears 104 thereon engaging the guide rod 100. The ears 104 snugly fit the guide rod, but the opening 99 is larger than the rod so that the sound box arm may 95 vibrate horizontally on the pivot 102 to a limited extent and the needle of the sound box can properly follow the groove of the record. Two stop lugs 105 are formed on the rear portion of the yoke 103 on opposite sides of the vertical axis of the sound box arm and cooperate with the rear face of the lug 98 to limit the lateral swinging movement of the arm relative to the yoke. Both the yoke 100 and the sound box arm are free to swing vertically upon the horizontal guide rod 100. A horizontal feed screw 106 is rotatably mounted on the bracket 101 and is connected by a pair of bevelled pinions 107 to the upper end of a short vertical shaft 108 also journaled in the bracket. The lower end of this shaft is connected by a pair of bevelled pinions 109 to the rear end of a horizontal shaft 110. This shaft is inclined in position 110 as shown; its rear end is journalled in the bracket 101 and its forward end in the lug 8 (see Fig. 5); and a bevelled gear 111 on its forward end meshes with a bevelled pinion 112 fixed to the turn table shaft a. The feed screw 106 is thus rotated during the reproduction of the records and it acts to advance 115 the sound box over the record through the medium of a segment nut 113 connected to the yoke 103. In the construction shown (see Fig. 10) the segment nut is formed upon the 120 forward end of a lever or arm 114 which is pivoted to a lug 115 on the yoke and the rear end of which is connected by a spring 116 to a stud 117 projecting from the rear 125 end of the sound box arm L'. The nut is 130

thus yieldingly held in engagement with the feed screw during the reproduction of the record. When the sound box is lifted and moved backwardly along the guide rod 100 to commence a record, the sound box arm and yoke 103 swing together about the guide rod 100 and a lug 118 on the yoke engages the rear end of the arm 114 and lifts the segment nut 113 on the forward end thereof out of engagement with the feed screw.

To raise the sound box out of engagement with the record, a bar M extends beneath the sound box arm and cooperates with a shoe m which is pivoted between its ends to a lug 119 on the lower side of the sound box arm L'. The inner end of the bar M is pivoted to the arm k and its outer end is pivoted to an L shaped bracket 120 which is connected to and depends from the top frame 2. During the reproduction of the record, the bar M occupies a horizontal position, below and out of contact with the shoe m, but, when the arm k and centering pin K are lifted, as described, at the beginning of the record changing operation, the inner end of the track bar is elevated to raise the sound box arm and parts connected thereto. This movement also tilts the yoke 103 and disengages the nut 113 from the feed screw 106. The sound box and sound box arm are then moved outwardly over the record, the movement of these parts being guided by the rod 100 and the track bar M.

The return shift of the sound box arm is effected by a lever N (see Figs. 2, 3 and 4) pivoted at its lower end to a lug on the casting 101 and having an enlarged upper end arranged to engage the lug 115 on the yoke 103. The arm N is operated from the vertical shift rod k' through the medium of a yielding connection comprising a spring 121 connected at its upper end to a rearwardly projecting stud 122 on the rod k' and at its lower end, to a crank arm n. The arms N and n are loosely mounted upon the same pivot pin 123 and the arm n is arranged to cooperate with a lug 124 on the lower pivoted end of the arm N. The shift of the return arm or lever M is controlled by an arm or lever N' which is pivotally mounted in horizontal position on the bracket 101. The free end of this lever is provided with a forwardly projecting lug 125 which is arranged to cooperate with a rearwardly projecting lug 126 on the arm or lever N. A spring 127 connected to the arm N' and to the frame 101 tends to depress the arm, but the latter is normally upheld against the tension of the spring 127 by a latch n'. The latter is pivoted between its ends on the frame 101 and has a hook-shaped lower end 128 arranged to engage a bevelled lug 129 on the arm N' and normally uphold the latter against the tension of the spring 127 in the position shown

in Figs. 2 and 4. The upper end of the latch is arranged in the path of movement of a lug 130 on the yoke 103 and is adapted to be tripped thereby at the end of the reproduction of a record.

The arm N' is provided with a depending portion or lug 131 which is arranged to engage a pin 132 on a horizontal arm 133. One end of the latter extends through the slot 134 in the guide lug 135 on the face of the bracket 101. The other end of the arm 133 is loosely pivoted to one arm of a bell crank 136. This bell crank is pivoted in horizontal position to a rearwardly projecting lug 137 on the bracket 101 and is connected (see Figs. 6 and 7) by a link 138 to an arm 139 on the shaft 74. The arm 133 is connected to the trip lever N' by a spring 140 and this spring holds the arm 133 in the normal position shown in Fig. 2, with the stop pin 132 thereon against the bar 131. In this position of the parts, the friction disk controlling levers J and J' are held in the position shown in Fig. 6 so that the turn table and sound box feeding means 90 actuated by the disk 15 are in operation and the shifter mechanism, actuated by the disk 68, is held out of operation.

As the sound box and sound box arm are fed inwardly from the position shown in Fig. 2, the lug 126 on the return lever N passes beneath the lug 125 on the control lever N'. At the end of the reproduction of a record, the lug 130 on the yoke 103 engages and trips the latch n' to release the controlling arm or lever N'. The latter is then drawn down by the spring 127 until arrested by the engagement of its free end with a spring stop 141. The parts are then in the position shown in full lines in Fig. 3. The shift of the controlling lever N' and the lug 131 thereon shifts the arm 133 laterally and, through the medium of the bell crank 136, draws the link 138 rearwardly and thereby shifts the controlling levers J and J' from the position shown in Fig. 6 to that shown in Fig. 6a. This shift occurs against the tension of the spring 140 which, as stated, tends to hold the controlling levers J and J' in normal position. But when the control lever N' drops from the position shown in Fig. 2 to that shown in full lines in Fig. 3, the tension of the spring 140 is somewhat reduced and the shift of the controlling lever is effected as described, 115 by the spring 127. The operation of the turn table and the sound box feed is thus interrupted and the shaft h driven from the friction disk 68, is thrown into operation to change the records and return the sound box to commence the next record.

The operation of shaft h rotates the cam 81, as described, through the medium of the gears 62 and 84 so that the rod k' is lifted to raise the record centering pin K, sound 130

box L and sound box arm L'. The vertical movement of the rod k' also places the actuating spring 121 of the return lever N under tension, but before sufficient tension is placed thereon to operate the return lever, the lug 122 on the rod engages a lug 142 on the controlling arm N' and moves the lug 125 on the latter, into the path of movement of the lug 126 on the return lever N. The latter is thus held in the position shown in Fig. 3 until the controlling lever N' is raised to the position shown in dotted lines in this figure. The spring 121 which has been placed under tension by the upward movement of the rod k', then acts on the lever N to move the yoke 103 back over the guide rod 100 and thus shift the sound box arm and sound box outwardly over the record on the turn table. At the end of the upward shift of the controlling arm N', the lug 129 thereon engages a lug 143 on the latch n' and shifts the latter back to locking position shown in Fig. 4. During the operations described, the carriage G has been operated by the crank arm h' and the intermediate connections, to move the record on the turn table back to its position in the magazine and move the next record from the other magazine on to the turn table.

When the rod k' and control lever N' are lifted by the cam 81 as described, the lug 131 is moved away from the pin 132 on the bar 133 so that the latter is relieved of the tension of the spring 127. At the same time, the spring 140 is placed under tension and it is so positioned that it tends to lift the bar 133 and move it back toward the lug 135. But when the bar is thus lifted to the dotted position shown in Fig. 3, a shoulder 144 on the bar 133 engages the end of the slot 134 in the lug 135 and the bar 133 then serves as a lock or latch to hold the friction disk controlling arms J and J' in the position shown in Fig. 6^a with the shifter mechanism in operation. At the end of the upward movement of the rod k', the controlling arm N' is re-engaged with the latch n', as described. When the roller on the end of the rod k' passes over the high point of the cam 81, it drops on to a shoulder 145 on the cam and momentarily arrests the descent of the rod. On this descent of the rod, the pin or lug 122 thereon engages the upper edge of the latch bar 133 and shifts it from the position shown in dotted lines in Fig. 3 to that shown in full lines in Fig. 4. That is to say, the shoulder 144 of the bar 133 is moved out of engagement with the lug 135 and a second shoulder 146 thereon is moved into engagement therewith, it being understood that the spring 140 tends to shift the bar 133 laterally toward the slotted guide lug 135. In this position of the arm 133, the friction disk controlling levers J and J' are

held in a position intermediate those shown in Figs. 6 and 6^a and both the friction disks 15 and 68 are in operation. The rotation of the turn table is thus started before the cam 81 is fully restored to the normal position shown in Fig. 2 and while the shifter rod k' still rests on the shoulder 145. At this time, while all other portions of the shifting operation are completed, the sound box is still held out of contact with the record and does not engage the latter until the lower end of the rod k' passes over the shoulder 145 of the cam and drops on to a shoulder 148 thereof. The turn table and the record thus commence to rotate and acquire momentum before the record is engaged by the sound box and thus the engagement of the sound box with the record will not prevent the proper rotation of the record.

When the lower end of the rod k' drops on to the shoulder 148 of the cam 81, pin 122 further depresses the arm 133 from the position shown in Fig. 4 and disengages its shoulder 146 from the lug 135. Spring 140 then moves the arm back to the normal position shown in Fig. 2, with the pin 132 engaging the lower end of the lug 131. In this position, as already stated, the friction disk controlling arms J and J' are in the position shown in Fig. 6 so that the friction disk 68 is moved out of engagement with the drive wheel 72 to thereby arrest the operation of the shifter mechanism. It should be noted that the cam 81 and rod k' operated thereby, serve to throw the shifter mechanism out of operation after a single revolution of the cam and since the latter is connected to the main operated shaft h of the shifter mechanism by gears 62 and 84, this shaft rotates through a half revolution as described, at each operation. Inasmuch as the latch n' is tripped at the end of the reproduction of each record, it is obvious that the machine will continue in operation to play the records in the machine as long as the motor B is running. A suitable switch (not shown) in the circuit of the motor is provided for starting and stopping the machine. A rod 149 (see Figs. 2 and 3) sliding horizontally in guide lugs 150 is provided at its inner end with a cam nose or finger 149' and is normally held in retracted position by a spring 150'. A crank arm 151 having a pin-and-slot connection with the rod is fixed to a rock shaft 152. By shifting the rod inwardly the cam finger 149' thereon is arranged to engage the rear end of the segment nut lever 114 to disengage the latter from the screw 106 so that the latter engages a lug 103' on the yoke 103 (see Fig. 10) and swings the yoke and arm L' to slightly raise the sound box L. The continued inward movement of the rod 149' will quickly shift the yoke and parts connected thereto inwardly to the position shown in Fig. 3 to 130

thereby trip the latch n' and set the shifter mechanism in operation. The rock shaft 152 extends to the exterior of the machine casing and can be manually operated by the user if desired, to throw the record and sound box shifter mechanism into operation before the reproduction of the record on the turn table is completed.

The outward or return shift of the sound box and sound box arm must be arrested at different distances from the center of the turn table. For this purpose, a stop member P having two stop arms p and p' (see Figs. 3, 8 and 10^a) is connected by horizontal pivot pins 153 to the bracket 120 and to one of the rear bars 4. A spring 154 tends to hold this stop device in the position shown in the drawings, with a stop lug 155 on the stop arm p against the edge of the supporting bar 4 (see Fig. 8). In this position, the stop arms cooperate with the yoke 103 and sound box L to arrest the return movement of these parts with the sound box in proper position to engage and commence a reproduction of the small record e' . The stop device P is also provided with a depending lug 156 (see Figs. 2, 3 and 8) which is arranged in the path of movement of the lug 157 on the upper rear portion of the carriage G. When the carriage is shifted from the position shown in the drawings to the other end of its movement, to place a large record on the turn table, the lug 157 engages the lug 156 on the stop member P and swings the stop arms p and p' downwardly out of the path of movement of the yoke 103 and sound box. The return movement of these parts is then arrested by fixed stops comprising one of the lugs 158 in which the rod 100 is mounted, and the bracket 120. Preferably, as shown, the stop arms p and p' and the bracket 120 are provided with felt or leather pads. This return shift of the sound box and sound box arm to different points is permitted because this movement is effected by the yielding spring connection 121 between the rod k' and the arm n .

The sound box is provided with needle changing mechanism similar to that set forth in Patent No. 1,182,551 above referred to. For this purpose the sound box has a projecting finger 159, which, as the sound box is lifted, is adapted to pass through a cam slot 160 in a cam plate 161 that depends from the top frame 2. Ordinarily, there are two needles, one above the other in the needle holder 162 of the sound box, the lower one being firmly secured in position by a spring-held clamp 163. As the sound box is raised, the spring-held clamp and a pivoted spring-held ejector 164 are successively engaged by a pair of lugs 165 and 166 on the cam plate 161 to thereby eject the lower used needle and move the upper new needle 65 into the grip of the clamp 163. At the same

time, a needle is ejected from a suitable needle magazine 167 (see Figs. 1 and 10) by means of a spring-held actuating dog 168 which is mounted upon the vertically shifting, horizontal arm k . As fully set forth in the prior patent referred to, the needle from the magazine passes through a guide tube 169 on the sound box and rests upon the needle clamped in the needle holder 162.

In the present construction improved means are provided for accumulating the used needles so that they will not drop down into and prevent the operation of the mechanism. For this purpose, a cup 170 (see Figs. 8, 9 and 9^a) having a movable bottom portion 171 is mounted on the lower end of the fixed cam plate 161. Both the cup 170 and the bottom portion 171 are pivotally mounted on the same vertical pivot pin 172 that is fixed to the cam plate and the bottom piece 171, which is formed with sheet metal, is provided with an integral bent ear 173 extending over the pivot end of the cup and also engaging the pivot pin 172. Light springs 174 and 175 connect the ear 173 and an ear 176 on the cup with a depending pin 177, the upper end of which is fixed to the cam plate 161. These springs are arranged in line with the pivot pin 172 and normally hold the cup and bottom plate in the central position shown in Fig. 8. At the end of the inward movement of the sound box, a depending lug 178 thereon engages the cup and its bottom plate and swings them to one side as shown in Fig. 9^a. When the sound box is lifted to release and discharge the used needle and supply a new needle, the cup 170 and bottom plate 171 swing back beneath the sound box and catch the used needle as it is discharged from the holder 162 thereof.

The cup bottom plate 171 is provided with a forwardly projecting portion 179 which is arranged in the path of a lug 180 on the central portion of the carriage G (see Figs. 6 and 8). The central portion of the carriage is also provided with a needle receiving cup or depression 181 which is normally closed by a bottom plate 182 having upwardly projecting ears at one end which are pivoted to ears on the carriage by a pivot pin 183. A spring 184 surrounding the pivot pin engages the upper face of the carriage and an upwardly projecting lug 185 on the rear end of the plate 182 and holds the latter in the normal closed position shown in Fig. 6. The lug 185 is arranged to be engaged by a cam lug 186 formed upon the horizontal portion of the L-shaped bracket 120 (see Fig. 8). Beneath this cam lug is arranged a large receptacle 187 for used needles having a flange 188 at its upper edge overlapping the central end portion of the frame 5. This receptacle is removably held in position by a pin 189 on the frame 130

extending through a perforation in the flange 188.

Whenever a needle is discharged from the needle holder of the sound box, it drops 5 as described, into the cup 170 being retained thereon by the removable bottom plate 171. The carriage G is, as stated, at each operation of the machine, shifted from one side to the other. When moved in either one or 10 the other direction, the lug 180 on the carriage engages the tail portion 179 of the plate 171 and shifts the latter so that the needle in the cup 170 drops into the cup or recess 181 in the slide or carriage G, 15 being retained therein by the plate 182. When the carriage is shifted to the position shown in Fig. 8, the needle thus collected remains in the recess 181. When the carriage is shifted in the opposite direction 20 from the position shown in Fig. 8 to the opposite side of the machine, another needle is discharged from the cup 170 into the cup 181. At the end of this movement, the cam lug 186 strikes the upwardly projecting lug 25 185 on the plate 182 and tilts the latter downwardly about the pivot 183 so that the two needles thereon are discharged into the large receptacle 187.

At each operation of the machine, the feed 30 screw operates to move the sound box inwardly until the pin 159 thereon is positioned inwardly beneath the lower open end of the cam slot 160 (see Fig. 5) and against a stop 190, thus limiting the inward movement 35 of the sound box. The latter is then in proper position to effect the needle changing operation and must be moved inwardly toward the center of the record to such position at each operation of the machine. But the 40 grooves of different records terminate at different distances from the centers of the record and of the turn table. To obviate disagreeable noises, means are provided for lifting the sound box to a slight extent, to 45 disengage the needle of the sound box from the record at the end of the record groove; such means being so arranged that it does not interfere with the complete inwardly shift of the sound box into proper relation 50 with the needle changing mechanism.

For this purpose, the shoe *m* is pivoted, as described, to the lug 119 on the sound box arm *L'* and is connected by a spring 191 to a lug 192 on the arm. A latch 193, 55 also pivoted on the lug 192 and yieldingly held in place by a spring 194, is arranged to engage the shouldered end of the pivot shoe *m* and hold the latter in the position shown in Fig. 10^a with the spring under tension. 60 A trip 195 is pivoted at 196 to a slide 197. A pin and slot connection 198 determines the extent of oscillating movement of the trip 195. The latter is provided with a bevelled end and a series of ratchet teeth on its lower 65 edge which cooperate with a lug 199 on the

lower end and on the face of the latch 193. The slide 197 is held in position by a series of guide lugs 200 on a part 201 so that it is free to reciprocate in horizontal position. The part or bracket 201 is secured to or rear 70 formed in piece with the arm *k*. A curved weighted arm 202 pivotally mounted upon the upper end of a lug 203 on the part 201 is arranged to engage a pin 204 on the side of the slide 197. On the rear face of the 75 slide and adjacent its outer end is pivoted a two-armed equalizing member 205. A rearwardly projecting stop lug 206 (see Figs. 8 and 10^a) on the end of the slide 197 normally holds the equalizing member 205 in the 80 position shown in Fig. 10^a and such that, as the sound box is moved inwardly in reproducing the record, the ends of the equalizing device will engage with two flat faces 207 and 208 formed respectively on the side of 85 the sound box arm *L'* and on the forward end of an arm 209. The latter is fixed to and extends forwardly from the yoke 103.

When the sound box commences a record, the parts are in the position shown in Fig. 90 10^a with the latch engaging the shoe *m* and holding it in the position shown, with the spring 191 under tension and the shoe out of contact with the track bar *M*. As the sound box arm and arm 209 move inwardly, the lug 95 199 engages the beveled end of the pivoted trip 195, lifts it and passes beneath the same into engagement with one of the teeth on its lower edge. Some time before the sound box completes the reproduction of the 100 record, the flat faces 207 and 208 on the sound box arm *L'* and on the arm 209 engage the ends of the equalizer bar 205 and the slide 197 and trip 195 thereon shift inwardly with the continued inward movement 105 of the sound box. The arm 209 on the yoke 103 travels in conformity with the pitch of the feed screw 106. The sound box arm, however, is free to shift laterally relatively to the yoke as described, to follow the groove 110 of the record which may vary in pitch and differ from the pitch of the feed screw. Usually the screw is so designed that it will feed the yoke somewhat slower than the sound box is fed by the groove of the record. 115

But even though the sound box arm moves faster than the arm 209 so that the lug 199 on the latch 193 moves farther and farther in beneath the trip 195, the ends of the equalizer 205 will be maintained in contact 120 with the flat faces 207 and 208 on these arms. When the sound box needle reaches the inner end of the record groove, the movement of the sound box and its arm *L'* are no longer propelled thereby and are momentarily arrested. But the movement of the arm 209 is continued by the feed screw 106, and the pressure of this arm against the lower 125 end of the equalizer lever 205 shifts the slide 197 inwardly, the point of contact of the 130

equalizer lever with the face 207 of the then stationary sound box arm acting as a fulcrum. This inward shift of the slide and trip 195 releases the latch 193 so that the inner end of the shoe is drawn upwardly by the spring 191 and the outer end is forced downwardly into engagement with the upper edge of the track bar M as shown in Fig. 10^b. This movement raises the sound box 10 slightly to move its stylus out of contact with the record. The inward shift of the sound box is again resumed when the slight lateral play between the sound box arm L' and the yoke 103 is taken up and this movement is continued by the screw 106 until the lug 130 trips latch n' as described, and throws the shifter mechanism into the operation. At the end of this forward movement of the sound box, the arm 159 on the sound box abuts against the stop flange 190 and the sound box is then in position to be lifted past the cam plate 161 to thereby change the needle. When the arm k and centering pin K are lifted, the inner end of the track bar M is lifted, the track bar swinging upwardly about its pivoted outer end to an inclined position. This upward movement of the track bar first swings the shoe m about its pivot against the tension 30 of the spring 191 and, since the sound box arm L' is nearer the center of motion of the upwardly swinging track bar M than the arm k, the trip 195 carried by the arm k is raised higher than the latch 193 on the arm 35 L' and is lifted out of engagement with the lug 199 on the latch. The latter then re-engages the inner end of the shoe m and the sound box is moved outwardly, as described, over the record on the turn table. When 40 this occurs, the weighted arm 202 which, upon the inward shift of the slide 197 has been raised to the position shown in Fig. 10^b by the pin 204, acts on this pin to move the slide 197 outwardly to the position shown in 45 Fig. 10^a. The parts are then in position for the succeeding operation.

Normally, the machine alternately plays large and small records. To permit the playing of the same record two or more times in succession, means is provided for throwing the record shifter mechanism out of operation. For this purpose the inner end of the hub of the crank arm h' is slotted and engages a pin 210 (see Fig. 7) extending through the shaft h. A shifter arm 211 vertically pivoted on a lug 212 on the lower frame 1 (see Figs. 5 and 7) is provided with a bent inner end having a pin 213 thereon arranged between a pair of flanges 55 214 on the hub of the crank arm so that the latter may be shifted into and out of engagement with the pin 210 by means of a shifter rod 215 connected to the opposite end of the lever 211 and extending to the 60 exterior of the machine casing. A latch

or locking bar 216 is pivoted between its ends to the arm 211 and its inner end is arranged to engage one or the other of two diametrically arranged notches 217 in the inner flange 214 of the hub. The other 70 end of the latch or locking bar 216 is arranged between a pair of studs 218 on a lug 219 which projects from the fixed frame 1. In the normal position shown in Fig. 7, the hub of the crank arm h' engages the 75 pin 210 to lock the crank arm to the shaft h. In this position the inner end of the latch bar 216 is disposed just inside the inner flange 214. At either end of the movement of the crank arm the lever 211 can be 80 shifted to disengage the same from the pin 210. During this movement of the lever the outer end of the latch bar 216 is held against movement by the studs 218 so that its inner end is shifted farther than the adjacent end 85 of the lever 211 and engages one or the other of the notches 217 in the inner flange 214. In this way the crank arm h' is disengaged from the shaft h and is held against rotation. In this condition the operation of the shaft h will shift the sound box and effect the operation of the needle changing mechanism as heretofore described but will not operate the slide or carriage G to change the records. When the 90 movement of the shaft h is arrested, the crank arm can be shifted to again engage its notched hub with the pin 210 to thereby re-connect the crank arm with the shaft. During this movement the inner end of the 95 lock bar 216 is disengaged from the notched flange 214. It should be noted that the notched hub and the pin 210 and the notched flange 214 and the latch 216 form interlocking devices so arranged that the crank 100 arm h' can be disconnected from the shaft h and reconnected therewith only when the shaft, which makes a half revolution at each 105 operation, is at the end of its movement in one or the other direction. The sound 110 box and record shifter mechanisms must therefore always operate in proper timed relation and this relation between the two cannot be disarranged by the means for throwing the record shifter mechanism into 115 and out of operation.

A pair of indicator dials 220 are mounted at the upper front portion of the frame and at opposite sides thereof. These dials are mounted on shafts 221 journalled in brackets 120 222 and each dial is connected to one of the record magazines so as to rotate as the latter are raised and lowered. In the construction shown, the shafts 221 are provided with pulleys 223 over which extend cords 224 that are connected at their lower ends to the magazines. Springs 221 (see Fig. 1^a) coiled about the shafts 221 take up slack in the cords 223 and rotate the disks as the magazines are raised. The disks are, of course, 125 130

rotated in the opposite direction against the tension of the springs when the magazines are lowered. The disks are provided on their front face with numbers or letters 5 which are exposed through openings 225 in the front wall of the machine casing, portions of which are indicated in Figs. 1 and 1^a.

In the drawings, the carriage G is shown 10 at the left-hand end of its movement with one of the records e' withdrawn from the magazine E' and in position on the turn table. In this position the dial 220 of the magazine E' indicates the record in playing 15 position and the dial of the magazine E indicates the record which will be played at the next operation. To distinguish between these indications a pair of indicator rods 226 are arranged to slide vertically 20 through guide lugs 227 on the end portions of the frame 2. These rods extend upwardly behind the indicator dials 220 and their upper ends are bent forwardly and are provided with depending indicating pointers 228. The lower ends of the rods 226 are connected to the outer ends of a pair of levers 229 which are pivoted on the ends of the front track bar 52. The inner ends of the levers are provided with inwardly 25 projecting lugs 230 which are arranged to be alternately engaged by the ears 54' on the ends of the carriage G. When the latter is at the right-hand end of its movement as shown, the adjacent rod 226 is raised so 30 that the pointer 228 at its upper end is not visible through the opening 225. But the rod 226 at the opposite side of the machine and corresponding to the magazine E' is lowered and its indicating pointer is exposed 35 to the adjacent opening 225. The indicator mechanism thus clearly shows the record in playing position and also shows the next record to be played. It also indicates which magazine may be adjusted to select the next 40 record.

It is obvious that changes may be made without departure from the essentials of the invention as defined in the claims and that parts may be taken without the adoption of 50 the invention in its entirety.

I claim as my invention:—

1. The combination with means for rotating records in playing position and a co-operating reproducer, of a shifter for moving 55 a record out of playing position and another record into such position, a shifter for raising and moving the reproducer to starting position and lowering the same into engagement with the record in playing position, a common actuating shaft connected to operate said record and reproducer shifters in timed relation, a motor for actuating said record rotating means, cooperating members arranged to be engaged and disengaged to positively connect and discon-

nect said motor and said shaft, means automatically acting at the end of a reproduction of a record for engaging said members to initiate the operation of said shifters and means actuated by said shaft for disengaging the same upon the complete operation of said shifters. 70

2. The combination with means for rotating records in playing position and a co-operating reproducer, of a shifter for moving 75 a record out of playing position and another record into such position, a shifter mechanism for raising and moving the reproducer to starting position and lowering the same into engagement with the record in playing, 80 position, a common actuating shaft connected to operate said record and reproducer shifters in timed relation, a motor for actuating said record rotating means, cooperating members arranged to be engaged and disengaged to positively connect and disconnect said motor and said shaft, a controller normally holding said members disengaged, trip mechanism automatically actuated at the end of a reproduction of a record for 85 shifting said controller to engage said members and means actuated by said shaft for restoring said trip mechanism and said controller to normal. 90

3. The combination with means for rotating records in playing position and a co-operating reproducer, of a shifter mechanism for moving records into and out of playing position, a shifter mechanism for raising and moving the reproducer to starting position and lowering the same into engagement with the record, a common actuating shaft connected to operate said record and reproducer shifter mechanisms in timed relation, a motor for actuating said 100 record rotating means, cooperating members for connecting said motor to said shaft, a latch controlling the engagement of said members, means for automatically tripping said latch at the end of a reproduction of a 105 record to thereby shift said controller and engage said members, a second latch controlling the disengagement of said members and means actuated by said shaft for resetting said first latch and tripping said second 110 latch. 115

4. The combination with means for rotating records, in playing position and a co-operating reproducer, of a shifter mechanism for moving the records into and out of 120 playing position, a shifter mechanism for raising and moving the reproducer to starting position and lowering the same into engagement with the record, a common actuating shaft connected to operate said record and reproducer shifter mechanisms in timed 125 relation, a motor for actuating said record rotating means, cooperating members for connecting said motor to said shaft, means for automatically engaging said members at 130

the end of a reproduction of the record to throw said shifter mechanisms into operation, a latch controlling the disengagement of said members and means actuated by said shaft for automatically tripping said latch upon the complete operation of said shifter mechanisms.

5. In a multiple record talking machine, the combination with means for rotating 10 records in playing position and a cooperating reproducer, of a shifter mechanism for moving the records into and out of playing position and for effecting the cooperation of said reproducer therewith, a latch, means 15 controlled thereby for throwing said shifter mechanism into operation, means for automatically tripping said latch, a second latch for maintaining said shifter mechanism in operation and means actuated by said shifter mechanism for restoring said first latch and tripping said second latch.

6. In a multiple record talking machine, the combination of a horizontal turn table for supporting and rotating disk records, 20 drive mechanism therefor, a reproducer, a shifter mechanism for moving records out of and into playing position on said turn table, a shifter mechanism for raising said reproducer, moving the same to starting position and lowering it into engagement with the record on said turn table, common driving means for said record and reproducer shifter mechanisms cooperating members adapted to be engaged and disengaged to 30 throw said driving means into and out of operation and means positively geared to said turn table drive mechanism for automatically engaging said members to thereby throw said shifter driving means into operation at the end of a reproduction of a record.

7. In a multiple record talking machine, the combination of a horizontal turn table for supporting and rotating disk records, 45 drive mechanism therefor, a reproducer, a shifter mechanism for moving records out of and into playing position on said turn table, a shifter mechanism for raising said reproducer, moving the same to starting position and lowering it into engagement with the record on said turn table, common drive means for said record and reproducer shifter mechanisms, means positively geared to said turn table drive mechanism for throwing 50 said shifter driving means into operation at the end of a reproduction of a record, and means automatically acting upon the engagement of the reproducer with the record for throwing said common shifter 55 driving means out of operation.

8. In a multiple record talking machine, the combination with a support for rotating disk records, drive mechanism therefor, a cooperating reproducer, a shifter mechanism 60 for moving disk records successively 65

out of and into playing position on said support, a second shifter mechanism for changing the needle of said reproducer and moving the same to starting position in engagement with the record on said support and means positively geared to said drive mechanism and actuated at the end of a reproduction of a record for throwing said shifter mechanism into operation.

9. In a multiple record talking machine, 75 the combination with a support for rotating disk records, drive mechanism therefor, a cooperating reproducer, a shifter mechanism for moving disk records successively out of and into playing position on said support, 80 a second shifter mechanism for changing the needle of said reproducer and moving the same to starting position in engagement with the record on said support, means positively geared to said drive mechanism and 85 actuated at the end of a reproduction of a record for throwing said shifter mechanisms into operation and means automatically acting upon the engagement of said reproducer with the record for throwing said shifter 90 mechanisms out of operation.

10. In a multiple record talking machine, the combination of a horizontal turn table for rotating disk records, drive mechanism therefor, a cooperating reproducer, shifter 95 mechanism for moving disk records out of and into playing position on said turn table and for raising said reproducer and moving the same to starting position in engagement with the record on said turn table, a motor 100 for said drive mechanism, cooperating members for connecting said motor to said shifter mechanism, means positively geared to said turn table drive mechanism and automatically actuated at the end of a reproduction of a record for engaging said members to throw said shifter mechanism into operation, and means automatically actuated by said shifter mechanism upon the engagement of said reproducer with the 105 record for disengaging said members.

11. In a multiple record talking machine, the combination with reproducing mechanism comprising a horizontal turn table for rotating disk records and a cooperating 115 sound box, of a disk record magazine vertically movable to bring the records therein opposite said turn table, shifter mechanism comprising means for raising and lowering said magazine step by step and for moving 120 records between said magazine and said turn table, shifter mechanism for raising and moving said sound box and lowering the same into engagement with the record on said turn table and means for automatically 125 actuating said reproducing means and said shifter mechanisms alternately and in cycle to reproduce successive records.

12. In a multiple record talking machine, the combination with reproducing mecha- 130

- nism comprising a horizontal turn table for rotating disk records and a cooperating sound box, of a disk record magazine vertically movable to bring the records there-
 5 in opposite said turn table, shifter mech-
 anism comprising means for raising and low-
 ering said magazine step by step and for
 moving records between said magazine and
 said turn table, shifter mechanism for rais-
 10 ing and moving said sound box and lower-
 ing the same into engagement with the
 record on said turn table, drive mechanism
 for said turn table, means positively geared
 to said turn table and automatically acting
 15 at the end of the reproduction of a record for
 throwing said shifter mechanisms into op-
 eration and means for throwing said shifter
 mechanisms out of operation upon the en-
 gagement of said sound box with the record.
 20 13. In a multiple record talking machine,
 the combination with reproducing mech-
 anism comprising a horizontal turn table for
 rotating disk records and a cooperating
 sound box, of a disk record magazine ver-
 25 tically movable to bring the records therein
 opposite said turn table, shifter mechanism
 comprising means for raising and lowering
 said magazine step by step, means for shift-
 ing the records between said magazine and
 30 said turn table, means for changing the
 needle of said sound box, and means for
 shifting the latter to starting position in
 engagement with the record on the turn
 table, and mechanism for automatically ac-
 35 tuating said reproducing means and said
 shifter mechanism alternately and in cycle
 to reproduce successive records.
 14. In a multiple record talking machine,
 the combination with reproducing mech-
 40 anism comprising a horizontal turn table for
 rotating disk records and a cooperating
 sound box, of a disk record magazine ver-
 tically movable to bring the records there-
 in opposite said turn table, shifter mech-
 45 anism comprising means for raising and low-
 ering said magazine step by step, means for
 shifting the records between said magazine
 and said turn table, means for changing the
 needle of said sound box, and means for
 50 shifting the latter to starting position in
 engagement with the record on the turn
 table, drive mechanism for said turn table,
 cooperating members for throwing said
 shifter mechanism into and out of opera-
 55 tion, means positively geared to said drive
 mechanism for automatically engaging said
 members at the end of a reproduction of a
 record and means controlled by said shifter
 mechanism for automatically acting upon
 60 the engagement of the sound box with a
 record to disengage said members.
 15. In a multiple record talking machine,
 the combination with a rotatable record sup-
 port and a cooperating reproducer, of a
 65 shifter mechanism for moving records out
 of and into playing position on said support,
 a shifter mechanism for raising and moving
 the reproducer to starting position and low-
 ering the same into engagement with the
 record on said support, a common actuating
 70 shaft connected to said record and repro-
 ducer shifter mechanisms to operate the
 same in timed relation, a motor, and means
 automatically acting at the end of the repro-
 duction of a record and upon the complete
 75 operation of said shifter mechanisms for
 alternately connecting said shaft and said
 support to said motor and disconnecting
 the same therefrom.
 16. In a multiple record talking machine,
 80 the combination with a rotatable record sup-
 port and a cooperating reproducer, of a
 shifter mechanism for moving records out
 of and into playing position on said sup-
 port, a shifter mechanism for raising and
 85 moving the reproducer to starting position
 and lowering the same into engagement with
 the record on said support, a common actu-
 ating shaft connected to said record and re-
 producer shifter mechanisms to operate the
 90 same in timed relation, a motor, a controller
 for alternately connecting said shaft and
 said support to said motor and disconnecting
 the same therefrom and devices connected to
 said support and to said shaft for shifting
 95 said controller to thereby alternately throw
 said support and said shaft into and out of
 operation.
 17. In a multiple record talking machine,
 the combination with a support for rotating
 100 disk records, drive mechanism therefor, a
 cooperating reproducer, shifter mechanism
 for moving disk records successively out of
 and into playing position on said support
 and for raising said reproducer and moving
 105 the same to starting position in engagement
 with the record on said support, means pos-
 itively geared to said drive mechanism for
 arresting said support and throwing said
 shifter mechanism into operation and means
 110 controlled by said shifter mechanism for
 arresting the latter and starting said sup-
 port.
 18. In a multiple record talking machine,
 the combination with a horizontal turn table
 115 and a cooperating sound box, of a disk rec-
 ord magazine vertically movable to bring
 the records therein opposite said turn table,
 shifter mechanism for adjusting said mag-
 azine, for moving records between the
 120 same and said turn table and for moving said
 sound box to starting position in engage-
 ment with the record on the turn table, drive
 mechanism for said turn table, means pos-
 itively geared to said drive mechanism for
 125 automatically arresting said turn table after
 the reproduction of a record and for throw-
 ing said shifter mechanism into operation,
 and means automatically actuated by said
 shifter mechanism for starting said turn
 130

table and for throwing the shifter mechanism out of operation.

19. In a multiple record talking machine, the combination with means for rotating 5 records in playing position and a cooperating reproducer, of shifter mechanism for moving records into and out of playing position and for moving the reproducer to starting position in engagement with the 10 record in playing position, automatically actuated controlling devices for alternately throwing said record rotating means and said shifter mechanism into and out of operation, said controlling devices being arranged to start said record rotating means before the reproducer is moved by said shifter mechanism into engagement with the 15 record in playing position.

20. In a multiple record talking machine, 20 the combination with a horizontal turn table for rotating disk records, a drive mechanism therefor and a cooperating sound box, of a vertically movable disk record magazine, shifter mechanism for adjusting said magazine, for moving records between the same and said turn table and for raising said sound box and moving the same to starting position in engagement with the record on the turn table and controlling devices automatically acting at the end of the reproduction of a record and upon the complete 30 operation of said shifter mechanism for alternately throwing said turn table drive mechanism and said shifter mechanism into and out of operation, said controlling devices being arranged to initiate the operation of said turn table before said sound box is moved by said shifter mechanism into engagement with the record on the turn 40 table.

21. In a multiple record talking machine, the combination with a turn table for rotating disk records and a cooperating sound box, of a shifter mechanism for moving disk 45 records out of and into playing position on said turn table, a second shifter mechanism for raising said sound box and moving the same to starting position in engagement with the record on said turn table, a common drive shaft for operating said shifter mechanisms in timed relation, a motor, and controlling devices for alternately connecting said turn table and said shifter drive shaft to said motor and disconnecting the same 50 therefrom, said controlling devices being arranged to connect said turn table to said motor before disconnecting said shifter drive shaft therefrom.

22. In a multiple record talking machine, 60 the combination with means for rotating records in playing position and a cooperating sound box, of shifter mechanism for moving records successively out of and into playing position and for moving said reproducer to starting position in engagement

with the record, an operating motor, cooperating friction disks for connecting said motor to said shifter mechanism, means controlled by said record rotating means for engaging said friction disks and means controlled by said shifter mechanism for disengaging the same. 70

23. In a multiple record talking machine, the combination with a horizontal turn table for rotating disk records, drive mechanism 75 therefor, and a cooperating sound box, of shifter mechanism for moving disk records into and out of playing position on said turn table, a second shifter mechanism for raising the reproducer and moving the same to starting position in engagement with the record on the turn table, a common actuating shaft connected to said record and sound box shifter mechanisms for operating the same in time relation, a motor, cooperating friction 80 disks for connecting said motor and said shaft, means controlled by said turn table drive mechanism for engaging said disks and means controlled by said shaft for disengaging the same. 90

24. In a multiple record talking machine, the combination with means for rotating records in playing position and a cooperating reproducer, of shifter mechanism for moving records out of and into playing position and for adjusting said reproducer, a motor, two pairs of friction disks for connecting said motor to said record rotating means and to said shifter mechanism, and means for alternately engaging and disengaging said pairs of friction disks. 95

25. In a multiple record talking machine, the combination with a horizontal turn table for rotating disk records and a cooperating sound box, of a disk record magazine, shifter mechanism for adjusting said magazine and for moving records between the same and said turn table, a second shifter mechanism for raising said sound box and moving the same to starting position in engagement with the record on said turn table, a common actuating shaft for operating said record and sound box, shifter mechanisms in timed relation, a motor, two pairs of friction disks connecting said motor to said turn table and to said shifter actuating shaft, a controller for alternately connecting and disconnecting said pairs of friction disks, and means connected respectively to said turn table and to said shaft for actuating said controller. 105 110 115

26. In a multiple record talking machine, the combination with means for rotating records in playing position and a cooperating reproducer, of shifter mechanism for moving records out of and into playing position and for raising said reproducer and shifting the same to starting position in engagement with the record in playing position, a motor, two pairs of friction disks for connecting said motor to said record rotat- 120 125 130

- ing means and said shifter mechanism and controlling devices automatically actuated by said record rotating means and by said shifter mechanism for alternately engaging 5 and disengaging said pairs of friction disks to thereby alternately throw said record rotating means and said shifter mechanism into and out of operation, said controlling devices being arranged to throw said record 10 rotating means into operation before said reproducer is engaged with the record in playing position.
27. In a multiple record talking machine, the combination with means for rotating 15 records in playing position and a cooperating reproducer, of shifter mechanism for moving records out of and into playing position and for raising said reproducer and moving the same to starting position in en- 20 gagement with the record in playing position, a motor, two pairs of friction disks for connecting said motor to said record rotating means and to said shifter mechanism, a controller for alternately engaging and 25 disengaging said pairs of friction disks, means acting at the end of the reproduction of a record for shifting said controller from normal to arrest said record rotating means and start said shifter mechanism, means con- 30 trolled by said shifter mechanism for effecting the return shift of said controller to arrest said shifter mechanism and start said record rotating means and means for momen- 35 tarily arresting the return shift of said controller with both pairs of friction disks in engagement to thereby start said turn table before said reproducer is engaged with the record thereon.
28. In a multiple record talking machine, 40 the combination of reproducing mechanism comprising means for rotating records in playing position and a cooperating sound box, two record magazines movable to select the records therein, means manually oper- 45 able during the reproduction of a record for shifting one of said magazines to select the succeeding record, shifter mechanism for moving records from said magazines to playing position and for moving said sound box 50 to starting position in engagement with the record in playing position and automatic means for alternately and repeatedly operating said reproducing and shifter mechanisms to reproduce successive records.
- 55 29. In a multiple record talking machine, the combination of reproducing mechanism comprising a rotatable record support and a cooperating sound box, two record magazines movable to select the records therein, shifter mechanism for alternately moving 60 said magazines and for shifting records between the same and said support, means controlled by said shifter mechanism for moving said sound box to starting position in engagement with the record in playing posi- 65
- tion, means controlled by said shifter mechanism for preventing the movement of the magazine from which a record has been withdrawn and driving mechanism and automatic means for alternately and repeatedly operating said reproducing and shifter mechanisms to play successive records. 70
30. In a multiple record talking machine, the combination with a rotatable record support, drive mechanism therefor and a co-operating reproducer, of two record magazines movable to select the records therein, shifter mechanism for moving records between said magazines and said support and for moving said reproducer to starting position in engagement with the record on said support and means controlled by said drive mechanism for throwing said shifter mechanism into operation. 75
31. In a multiple record talking machine, the combination with a rotatable record support, drive mechanism therefor and a co-operating reproducer, of two record magazines movable to select the records therein, shifter mechanism for moving records be- 80 tween said magazines and said support and for moving said reproducer to starting position in engagement with the record on said support and means controlled respectively by said drive mechanism and said shifter mechanism for throwing the latter into and out of operation. 85
32. In a multiple record talking machine, the combination of reproducing mechanism comprising a rotatable record support, drive mechanism therefor and a cooperating reproducer, two record magazines movable to select the records therein, a needle magazine, shifter mechanism comprising means for adjusting said record magazines and for moving records between the same and said support and means for changing the needle of said reproducer and moving the same to starting position in engagement with the record on said support and drive mechanism and controlling devices for automatically operating said reproducing and shifter mechanisms alternately and repeatedly to reproduce successive records. 90
33. In a multiple record talking machine, the combination with a rotatable record support, drive mechanism therefor and a co-operating reproducer, of two record magazines movable to select the records therein, shifter mechanism for adjusting said magazines, moving the records between the same and said support and for moving said reproducer to starting position in engagement with the record on said support and means controlled respectively by the drive mechanism for said record support and by said shifter mechanism for automatically and alternately throwing said mechanisms into and out of operation. 115
34. In a multiple record talking machine, 120
- 125

the combination with reproducing means comprising a support for rotating disk records in playing position and a cooperating sound box, two record magazines for holding disk records of different sizes, said magazines being movable to select the records therein, shifter mechanism for moving records between said magazines and said support and for variably moving said sound box to starting position in engagement with the record on said support and driving means and controlling devices for automatically operating said reproducing and shifter mechanisms alternately and in cycle to play successive records.

35. In a multiple record talking machine, the combination of a rotatable record support and a cooperating sound box, of a record magazine, means for shifting records from said magazine to said support and from said support back to said magazine, means for raising said reproducer and moving the same to starting position in engagement with the record on said support, drive mechanism for said record and reproducer shifting means and devices for connecting and disconnecting said drive mechanism and said record shifting means to throw the latter out of operation and permit the continued operation of said reproducer shifting means to repeat the reproduction of the same record.

36. In a multiple record talking machine, the combination with a rotatable record support and a cooperating reproducer, of shifter mechanism for moving records into and out of playing position on said support, shifter mechanism for moving said reproducer to starting position in engagement with said support, drive mechanism connected to said record and sound box shifter mechanisms for operating the same in timed relation, manually operable means for connecting and disconnecting said drive mechanism and said record shifting mechanism and interlocking devices associated with said means.

37. In a multiple record talking machine, the combination with a rotatable record support and a cooperating reproducer, of shifter mechanism for moving records into and out of playing position on said support, shifter mechanism for moving said reproducer to starting position in engagement with said support, drive mechanism connected to said record and sound box shifter mechanisms for operating the same in timed relation, means for automatically throwing said drive mechanism into and out of operation, manually operable means for connecting and disconnecting said drive mechanism and said record shifter mechanism and interlocking devices associated with said manually operable means.

38. In a multiple record talking machine,

the combination with a turn table for rotating disk records in playing position and a cooperating sound box, of a disk record magazine vertically movable to select the records therein, shifter mechanism for adjusting said magazine and for moving records between the same and said turn table, a needle magazine, shifter mechanism for raising said sound box, changing the needle thereof and moving the same to starting position in engagement with the record on said turn table, a common drive mechanism for said record and sound box shifter mechanisms, and manually operable means for connecting and disconnecting said record shifter mechanism and said drive mechanism.

39. In a multiple record talking machine, the combination with means for rotating records in playing position and a cooperating reproducer, of shifter mechanism for moving records into and out of playing position, a controlling device means for automatically actuating said controlling device to throw said shifter mechanism into and out of operation and separate manually operable means for arresting the reproduction of a record and throwing said shifter mechanism into operation.

40. In a multiple record talking machine, the combination with a rotatable record support and a cooperating sound box, of means for moving records successively into and out of playing position on said support, shifter mechanism for moving the records to playing position in engagement with the record on said support, a controlling device means automatically acting at the end of the reproduction of a record for actuating said controlling device to throw said shifter mechanisms into operation and separate means for manually arresting the reproduction of the record and throwing said shifter mechanism into operation.

41. In a multiple record talking machine, the combination with means for rotating records in playing position and a cooperating reproducer, a shifter mechanism for moving records successively into playing position and separate movable indicating devices for respectively designating and distinguishing between the record in playing position and the next record to be placed therein.

42. In a multiple record talking machine, the combination with means for rotating records in playing position and a co-operating reproducer, of a record magazine movable to select the records, a shifter mechanism for moving selected records into playing position, means manually operable during the reproduction of a record for selecting the next record to be placed in playing position, and two movable indicating devices associated with said magazine for respec-

tively designating and distinguishing between the record in playing position and the next record to be placed therein.

43. In a multiple record talking machine, 5 the combination with a rotatable record support and a cooperating reproducer, of two magazines, shifter mechanism for alternately moving records from said magazines on to said support, means manually oper- 10 able during the reproduction of a record for shifting one of said magazines to select a succeeding record and two movable indicating devices associated with each of said magazines for respectively designating and dis- 15 tinguishing between the record on said support and the succeeding record.

44. In a multiple record talking machine, the combination with a horizontal turn table, two vertically movable magazines on 20 opposite sides of said turn table, a slide arranged to engage a record in one of said magazines and a record on said turn table, mechanism for alternately shifting said slide in opposite directions comprising a 25 pivoted oscillating lever connected to said slide, a drive shaft and a crank arm on said drive shaft, an intermediate pivoted arm, links connecting said pivoted arm to said lever and to said crank arm and means for 30 intermittently imparting half revolutions to said shaft.

45. In a multiple record talking machine, the combination with a support for rotating records in playing position and a cooperat- 35 ing sound box, of a shifter arranged to engage and move records from said magazine to playing position on said support, an oscillating arm connected to said shifter, an operating crank arm, a link interposed be- 40 tween said arms and having a lost motion connection with one arm, means for automatically and intermittently operating said crank arm and means acting at the end of the travel of said shifter for removing the 45 same in backward direction out of contact with the record on said support.

46. In a multiple record talking machine, the combination with a support for rotating records in playing position and a cooperat- 50 ing sound box, of a shifter arranged to engage and move records from said magazine to playing position on said support, an oscillating arm connected to said shifter, an operating crank arm and link interposed be- 55 tween said arms and having a lost motion connection with one arm, means for automatically and intermittently operating said crank arm and a cam device arranged to engage said shifter at the end of its travel and 60 move the same in backward direction out of contact with the record on said support.

47. In a multiple record talking machine, the combination with a turn table and a co- 65 operating sound box, of a disk record maga- zine, a shifter for engaging and moving the

disk records in opposite directions between said magazine and said turn table, a center pin for holding the records in place on said turn table, an actuating member having a lost motion connection with said shifter and 70 arranged to operate the same and said center pin in timed relation and means operated by said actuating member for moving said shifter out of contact with the record on said turn table. 75

48. In a multiple record talking machine, the combination with a turn table and a co- 80 operating sound box, of a disk record magazine, a shifter for engaging and moving the disk records in opposite directions between said magazine and said turn table, a center pin for holding the records in place on said turn table, an actuating member having a lost motion connection with said shifter and 85 arranged to operate the same and said center pin in timed relation and a cam device connected to said center pin for moving said shifter out of contact with the record on said turn table.

49. In a multiple record talking machine, 90 the combination with means for rotating records in playing position and a cooperat- 95 ing reproducer, and means for moving records into and out of playing position, of a shifter for moving said reproducer to start- 100 ing position in engagement with the record in playing position and a separate shifter actuated by said record rotating means and automatically controlled by the groove of the record in playing position for disengag- 105 ing said reproducer from the record at the end of its record groove.

50. In a talking machine, the combination with a support for rotating records in play- 110 ing position and a cooperating reproducer, 105 of a shifter for moving said reproducer to starting position in engagement with the record on said support, a screw for feeding said reproducer over the record, said re- 115 producer having a limited lateral move- ment independent of said feed screw, a lifter for disengaging said reproducer from the record and means actuated by said feed screw and automatically controlled by said reproducer for throwing said lifter into op- eration at the end of the record groove.

51. In a talking machine, the combination with a support for rotating records in play- 120 ing position, drive mechanism therefor, and a cooperating reproducer, of shifter mecha- 125 nism for moving records into and out of playing position on said support and for moving said reproducer to starting position in engagement with the record in playing position, means actuated by said drive mechanism for throwing said shifter mech- 130 anism into operation, a spring actuated lifter for disengaging said reproducer from the record in playing position, a latch for holding said lifter inoperative and means for

tripping said latch actuated by said drive mechanism and automatically and variably controlled by the record grooves in accordance with the different lengths thereof.

5 52. In a multiple record talking machine, the combination with means for rotating records in playing position and a cooperating sound box, of shifter mechanism for moving records into and out of playing position and for adjusting said sound box, mechanism for automatically charging said sound box with needles and for discharging used needles therefrom, a holder for temporarily receiving used needles discharged 10 from said sound box, a receptacle mounted on the machine frame and movable means operated by said shifter mechanism for receiving used needles from said holder and conveying the same to said receptacle.

15 53. In a multiple record talking machine, the combination with a turn table and a cooperating sound box, of a record magazine, a shifter for moving records between said magazine and said turn table, a shifter for 20 moving said sound box to starting position, mechanism for charging said sound box with needles and for discharging used needles therefrom, a holder mounted on the machine frame for temporarily receiving needles discharged 25 from said sound box, a receptacle mounted on the machine frame and means on said record shifter for receiving used needles from said holder and conveying the same to said receptacle.

30 54. In a multiple record talking machine, the combination with a turn table and a cooperating sound box, of two record magazines on opposite sides of said turn table, a shifting slide alternately movable in opposite directions for moving records between 35 said magazines and said turn table, a shifter for raising said sound box and moving the same outwardly to starting position, mechanism cooperating with said sound box at the inner end of its movement for charging the same with needles and discharging used needles therefrom, a holder mounted on the machine frame for temporarily receiving needles discharged from said sound box, a 40 receptacle mounted on the machine frame and means on said shifting slide for receiving used needles from said holder and conveying the same to said receptacle.

45 55. In a multiple record talking machine, the combination with a turn table and a cooperating sound box, of a record magazine at one side of said turn table, mechanism for shifting records between said magazine and said turn table, an oscillating cam connected to said magazine and a counter balancing spring for said magazine connected to the machine frame and to said cam.

50 56. In a multiple record talking machine, the combination with a horizontal turntable and a cooperating sound box, of a shifter

horizontally movable for placing records into and out of playing position on said turntable, said shifter having parts arranged to engage the edges of relatively large and small record disks and contact 70 with the upper face of said turntable as said shifter is actuated, and means acting at the end of the movement of said shifter in one direction for relatively shifting the same and said turntable in vertical direction, 75 whereby said shifter is maintained out of contact with the turntable during the reproduction of the record.

57. In a multiple record talking machine, the combination with a horizontal turn 80 table and a cooperating sound box, of a shifter movable over and in contact with the upper face of said turn table for moving relatively large and small disk records into and out of playing position thereon, means 85 for actuating said shifter and means for lifting the same out of contact with said turn table during the reproduction of a relatively small record.

58. In a multiple record talking machine, 90 the combination with a turn table and a cooperating sound box, of two record magazines on opposite sides of said turn table for holding relatively large and small disk records, a shifter for moving records between 95 said magazine and said turn table, said shifter having parts adapted to engage a large and a small record and movable over and in contact with the upper face of said turn table, means for moving said shifter in 100 opposite directions to alternately place large and small records in playing position on said turn table and means acting at the end of the movement of said shifter in one direction for lifting the latter out of contact with 105 said turn table.

59. In a multiple record talking machine, the combination with means for rotating records in playing position and a co-operating reproducer, of means shiftable to select 110 a record, shifter mechanism for moving selected records into playing position, and separately moving indicating devices, one operated by said movable selecting means and the other by said shifter mechanism for 115 respectively designating and distinguishing between the record in playing position and the next record to be placed therein.

60. In a talking machine, the combination with a support for rotating records in playing position and a co-operating reproducer, of a feed screw for said reproducer, the latter having a limited lateral movement independent of said feed screw, and a lifter under the joint control of said feed screw and said reproducer for automatically and variably disengaging said reproducer from the records and in accordance with the varying lengths of the record grooves.

61. In a talking machine, the combina- 130

tion with a rotatable record support, driving means therefor and a co-operating reproducer, of a lifter for disengaging the reproducer from the records on said support and 5 means for automatically and variably operating said lifter in accordance with the different lengths of the record grooves, com-

prising a controlling member, a two-armed equalizer pivoted on said controlling member and parts connected to and moved respectively by said reproducer and said driving means and each adapted to engage one of the arms of said equalizer.

JOHN GABEL.
